DESIGN FOR A CARPET SWEEPER

Alfred H. Haberstump, Detroit, Mich., assignor to The Murray Corporation of America, Detroit, Mich., a corporation of Delaware

Application October 10, 1938, Serial No. 80,345

Term of patent 14 years

To all whom it may concern:

Be it known that I, Alfred H. Haberstump, a citizen of the United States of America, residing in Detroit, in the county of Wayne, State of Michigan, have invented a new, original, and ornamental Design for a Carpet Sweeper, of which the following is a specification, reference being had to the accompanying drawing, forming a part thereof, wherein:

Figure 1 is a plan view of a carpet sweeper showing my new design; and

I claim:

The ornamental design for a carpet sweeper, substantially as shown.

ALFRED H. HABERSTUMP.
